SERVING BOWL

Clarence J. Schroeder, Box 68, Murphy, N.C.

Filed July 26, 1963, Ser. No. 75,991

Term of patent 14 years

(Cl. D44—15)

FIG. 1

FIG. 2

FIG. 3

FIG. 4

FIG. 5

FIG. 1 is a perspective view of a serving bowl embodying my new design.

FIG. 2 is a side elevational view of the serving bowl shown in FIG. 1.

FIG. 3 is a top plan view of the serving bowl shown in FIG. 1.

FIG. 4 is a cross-sectional view taken along the line 4—4 in FIG. 3.

FIG. 5 is a cross-sectional view taken along the line 5—5 in FIG. 3.

I claim:

The ornamental design for a serving bowl, as shown.
